UNITED STATES PATENT OFFICE

2,060,070

APPARATUS FOR PRODUCING SUBSTANTIALLY PURE MAGNESIUM

Fritz Hansgirg, Radenthein, Austria, assignor to
 American Magnesium Metals Corporation,
 Pittsburgh, Pa., a corporation of Delaware

Original application December 28, 1933, Serial No.
 704,298. Divided and this application December
 17, 1934, Serial No. 757,783

6 Claims. (Cl. 266—19)

This invention relates to apparatus for producing substantially pure magnesium, and this application is a division of my copending application Serial No. 704,298, filed December 28, 1933, and is a continuation-in-part of a copending application Serial No. 655,067, filed by me February 3, 1933.

One object of the present invention is to separate substantially pure magnesium from non-volatile concomitant substances.

Another object of my invention is to enable magnesium to be distilled so as to condense the distillate as a liquid deposit.

A further object of the invention is to provide apparatus for the distillation of material containing metallic magnesium, especially apparatus for continuous operation.

The process forming the subject matter of my aforesaid application Serial No. 655,067 comprises passing crude metallic magnesium or material high in magnesium content through a heated zone in which magnesium is vaporized under the prevailing pressure conditions, removing the resulting vapor by a non-oxidizing gas from the heated zone, separating out dusty impurities from said vapor, thereafter passing the vapor into a condensation zone, and cooling it to the condensation point. The vapor is preferably prevented from cooling below the solidification point of the magnesium by being heated on its way to the condensing zone, and is then suddenly cooled to condensation point.

The process performed in this manner has special reference to the refining of magnesium by distillation in a continuous as contrasted with batch operation, the metal being condensed as a liquid deposit of maximum purity. If desired this process may be performed at reduced pressure.

While various types of apparatus might be employed for carrying out this process, a typical apparatus according to the original invention consists substantially of an externally heated distillation still which is provided with a conveyor and connected, by means of a heated pipe line, with a condenser from which the molten magnesium runs off into a collector, for example, through a barometric discharge, a filter being interposed between the said distillation chamber and the said condenser. The still, pipe line, filter, condenser, discharge and receiver are preferably housed in a common heating chamber, such as an electric radiation furnace.

According to the present invention, the magnesium vapors issuing from the distillation chamber are freed from impurities present in the

form of dust while passing to the condenser by using for this purpose the known principle of dust removal by reversing the direction of flow and/or reducing the velocity of flow of the vapors. By replacing filtration by such a method of removing dust the vapors merely encounter a small resistance to flow which remains unchanged during the entire period of working and does not therefore give rise to any irregularities during the process. Moreover, the thermal economy of the process is improved because preheating the fresh filtering material required for replenishing consumed material when using granular filters, is dispensed with.

For carrying out the present process dust removing apparatus of known construction in which the dust is precipitated by the principle of reversal of the direction of flow and/or of reducing the velocity of flow, for example centrifugal (cyclone) gas cleaners, can be inserted between the distillation chamber and the condenser; the dust removing chambers of this apparatus must, however, be heated in order to prevent any condensation of the metal vapors in the dust precipitators.

In order to complete the operation of the removal of dust two or more such apparatus of identical or different construction can be used.

In order more clearly to understand the nature of the invention, reference is made to the accompanying drawings, which illustrate diagrammatically and by way of example, an embodiment of apparatus suitable for carrying out the process of the invention. In the drawings Fig. 1 is a vertical section taken on line I—I of Fig. 3; Fig. 2 a horizontal section along the line II—II of Fig. 1; and Fig. 3 a longitudinal section showing means for feeding the material continuously.

A pipe 2 leads from the middle of the distillation chamber 1, through which the material to be distilled is continuously fed tangentially into a cylindrical dust precipitating chamber 3 which tapers conically in a downward direction. The lower end of the chamber is connected with the dust collecting chamber 4. The vertical limb of a bent pipe 5 passes through the centre of the cover of chamber 3 and constitutes the connection between said chamber and the condenser 6. The vapors bathe the jacket of the hollow condensing member 7, whereon condensation proceeds, the liquid metal being collected in the receiver.

The dust contained in the vapors which enter the dust-removing chamber 3 is precipitated chiefly on the cylindrical jacket of the chamber by the action of centrifugal force, and the dust

falls into the collecting chamber 4, whilst purified vapors pass on to the condenser via pipe 5.

The distillation can be effected either with or without the aid of reduced pressure.

5 The distillation chamber 1, dust separator 3, condenser 6, and the pipes connecting them are disposed within a heating furnace 8, as referred to hereinabove, for example of the electric radiation type.

10 Various means may be used for moving the material to be distilled continuously through the distillation chamber, that shown being one of the means disclosed in my aforesaid application Serial No. 655,067. Having reference to Fig. 3, distillation chamber 1 is in the form of an elongate tube in which there is mounted a screw conveyor 9 to which the material to be distilled is fed from a charging hopper 10 supplied with material from a storage bin 11 through a lock chamber 12 controlled by valves 13 and 14, so that material may be charged into hopper 10 from storage bin 11 while preventing entry of air into the distillation apparatus. The lower end of the charging hopper opens into a screw conveyor 15 which conveys the material to a pipe 16 which delivers the material to conveyor 9, by which it is conveyed continuously through distillation chamber 1. Conveyors 9 and 15 may be driven continuously by any suitable means, for example through pulleys 17 and 18.

25 Distillation chamber 1 extends entirely through furnace 8 and the distillation residue is discharged into a pipe 19 through which it passes into a collecting chamber 20, from which it is 30 discharged through a lock chamber 21 controlled by valve members 22 and 23.

35 Collecting chamber 20, lock chambers 12 and 21, and charging hopper 10 may be connected with a vacuum pump, not shown, through pipes 40 24, 25, 26 and 27 provided with valves for applying the vacuum to these units according to need. A stream of gas which is inert to metallic magnesium, suitably hydrogen, may be introduced into the apparatus to provide a flow for directing the flow of the magnesium vapors through pipe 2, dust removing element 3, and pipe 5, into condenser 6, and to conduct the operation in an inert atmosphere. In the apparatus shown, the inert gas is introduced through pipes 28 and 29 45 into both ends of distillation chamber 1. As shown in Fig. 3, the inert gas may be introduced as need be into lock chambers 12 and 21.

50 Mounted in condenser 6 is a cylindrical tube 32 the lower end of which is closed by a curved bottom, the condenser being disposed so that the incoming vapors bathe its bottom surface. Mounted coaxially within tube 32 is a tube 33 also closed at its lower end and coaxially surrounding a tube 34 which is open at its lower end. Cooling fluid is introduced into tube 34, and is withdrawn from tube 33 through an outlet 35. Tube 33 is mounted close to but out of contact with the wall of tube 32, so that in condensation 55 of the magnesium vapor on tube 32 the removal of heat by the cooling medium circulated through tubes 33 and 34 takes place principally by radiation. Tubes 33 and 34 are vertically adjustable within tube 32, as shown, so that the cooling action may be regulated according to need. The outlet 36 from the condenser dips into a receiver 37 mounted within furnace 8 and provided with a flow-controlling valve 38. By arranging the condenser at a level more than six meters above

the outlet level, a suitable automatic barometric outlet device is obtained.

According to the provisions of the patent statutes, I have explained the principle and construction of my invention, and have illustrated and described what I now consider to represent its best embodiment. However, I desire to have it understood that, within the scope of the appended claims, the invention may be practiced otherwise than as specifically illustrated and described.

I claim:

1. Apparatus for refining impure magnesium comprising a heating chamber, means for conveying the material to be refined through the said chamber, a condenser opening into a receiver for the condensed product of treatment, a pipe line for conveying vapor from the heating chamber to the said condenser, and a dust separating device interposed into said pipe line being adapted to precipitate the dust by provoking variations of the flow of the vapor capable of producing depositions of the suspended solids owing to their natural gravity.

2. Apparatus for refining impure magnesium comprising a heating chamber, means for conveying the material to be refined through the said chamber, a condenser opening into a receiver for the condensed product of treatment, a pipe line for conveying vapor from the heating chamber to the said condenser, and a centrifugal (cyclone) gas cleaner interposed into said pipe line.

3. Apparatus for refining impure magnesium comprising a heating chamber, means for conveying the material to be refined through the said chamber, a condenser opening into a receiver for the condensed product of treatment, a pipe line for conveying vapor from the heating chamber to the said condenser, and a centrifugal (cyclone) gas cleaner, interposed into said pipe line, the dust precipitating chamber of which is heated.

4. Apparatus for the distillation of magnesium comprising a distillation chamber provided with means for conveying through it the material to be distilled, a pipe line attached to the exit of the distillation chamber and terminating in a condenser which works into a receiver for the distillate, and a dust separating device adapted to precipitate the dust by provoking variations of the flow of the vapor capable of producing depositions of the suspended solids owing to their natural gravity, and being interposed between the said distillation chamber and the said condenser; the distillation chamber, dust separating device and condenser together with the connecting pipe being housed in a common heating casing.

5. Apparatus for refining magnesium comprising a heating chamber provided with means for conveying through it the material to be refined, and with locking means for inserting the material to be refined into the heating chamber and for removing the residue of treatment from said chamber, a condenser provided with collecting means for the refined product, a pipe line for conveying vapor from the heating chamber to the condenser, a dust separating device adapted to precipitate the dust by provoking variations of the flow of the vapor capable of producing depositions of the suspended solids owing to their natural gravity, and being interposed between the heating chamber and the condenser, and a

vacuum pipe for maintaining the system under vacuum.

6. Apparatus for refining magnesium comprising a heating chamber provided with means for conveying through it the magnesium material under treatment, and working into a condenser provided with collecting means for the refined product, a pipe line for connecting the condenser to the heating chamber, and a dust separating device adapted to precipitate the dust by pro-

voking variations of the flow of the vapor capable of producing depositions of the suspended solids owing to their natural gravity, and being interposed between the heating chamber and the condenser, all parts coming into contact with the material under treatment and the vapors driven off therefrom being constructed of a steel free from nickel and copper.

FRITZ HANSGIRG.
